UNITED STATES PATENT OFFICE

FREDERICK LOBL, OF MIDDLEBORO, MASSACHUSETTS

DESIGN FOR A COMBINED MENTHOL PENCIL AND INHALER

Application filed October 5, 1932. Serial No. 45,219. Term of patent 14 years.

To all whom it may concern:

Be it known that I, FREDERICK LOBL, a citizen of the United States, residing at Middleboro, in the county of Plymouth and State of Massachusetts, have invented a new, original, and ornamental Design for a Combined Menthol Pencil and Inhaler, of which the following is a specification, reference being had to the accompanying drawing, forming part thereof.

Fig. 1 is a perspective view;
Fig. 2 is a side elevation with cap removed; and

Fig. 3 is a bottom view of the combined menthol pencil and inhaler embodying my new design.

I claim:

The ornamental design for a combined menthol pencil and inhaler, as shown.

FREDERICK LOBL.
